UNITED STATES PATENT OFFICE.

BERNARD J. GARNER, OF CROSS PLAINS, TEXAS.

CLAMP.

Application filed April 25, 1925. Serial No. 25,837.

To all whom it may concern:

Be it known that I, BERNARD J. GARNER, a citizen of the United States, residing at Cross Plains, in the county of Callahan and

5 State of Texas, have invented certain new and useful Improvements in a Clamp, of which the following is a specification.

The present invention relates to an improvement in clamps and is intended for 10 use in holding the line or cable to which is attached the tools in drilling deep wells of every description. The clamp is adapted to be suspended below the temper screw by links, and is adapted to hold the line or cable 15 so firmly that the weight of the tools cannot slip the line through it so that the tool can only descend as set out by the temper screw.

An important object of the invention is to 20 provide a clamp of this nature which is exceedingly simple in its construction, satisfactory in its operation, efficient, reliable, strong, durable, easy to manipulate, not likely to become easily out of order, compact, and otherwise well adapted to the 25 purpose for which it is designed.

With the above and numerous other objects in view as will appear as the description proceeds, the invention resides in certain novel features of construction, and in 30 the combination and arrangement of parts as will be hereinafter more fully described and claimed.

In the drawing:—

Figure 1 is a top plan view of the clamp 35 embodying the features of my invention.

Figure 2 is a side elevation thereof showing one of the slips in section.

Figure 3 is a horizontal section through the clamp, and

40 Figure 4 is another side elevation of the device.

Referring to the drawing in detail it will be seen that the numerals 5 designate a pair of jaws. The outer side edges of these jaws 45 5 are provided with notches 6. Transversely disposed slip receiving portions 7 are provided on adjacent ends of the jaws 5 and the notches 6 are disposed closer to these ends of the jaws than to the other 50 ends. The transversely extending slip receiving portions 7 are provided with outwardly extending curved hooks 8 at adjacent ends. The inner edges of the portions 7 are grooved longitudinally as at 9, extending from the end provided with the hooks and terminating a slight distance

from the other ends as is clearly shown in Figure 2. These grooves taper from their bottom ends upwardly and receive similarly tapered slips 10 having their upper ends 60 provided with transversely extending apertured ears 11 which are positioned over the upper ends of the portions 7 and held in place by screws 12, the line or cable 13 is adapted to be received in the grooves of 65 the slips 10 in the usual manner. The hooks 8 of course, are adapted to be engaged in the links suspended from the temper screw.

A yoke or substantially rectangularly shaped frame 14 is provided on its end portions with inwardly disposed fulcrums 15 adapted to be received in the notches 6 as is clearly shown in Figure 3. A pin 16 extends centrally and transversely across the yoke or frame 14 and has disposed thereon 70 a sleeve or roller 17 for engaging the inner sides of the jaws 5 thereby holding the notches 6 in engagement with the fulcrums 15 and preventing the disassembling of the jaws from the yoke until this pin 16 is 75 removed. The pin 16 is preferably held in place by cotter pins 18 extending through the ends thereof to the outside of the longitudinal portions of the rectangular frame 14 as will be evident from an inspection of 80 Figures 1 and 4. The ends 19 of the jaws 5 are provided with notches 20, the entrances to which are disposed toward each other as may be seen in Figure 1. A screw block 21 is provided with oppositely disposed 85 trunnions 22 receivable in the notches 20 on one end 19 while a seat block 23 has its oppositely disposed trunnions 24 receivable in the other notch 20. The trunnions 22 and 24 are held against displacement from the 90 notches 20 by cotter pins 25. The screw block 21 is provided with a longitudinally extending screw threaded bore for receiving a T-screw 26. The seat block 23 is provided with a seat 27 for receiving the end of the 95 T-screw 26 which is preferably pointed for seating in the recess 28. A spring 29 is attached to the outer end of the screw block 21 and as at 30 and to an intermediate portion of the adjacent jaw 5 as at 31 and tends 100 to swing the inner end of the block 21 outwardly so that the end of the screw 26 will be properly seated in the lock 23.

By turning the screw 26 so that it will move toward the block 23 it will be seen 110 that the jaws 5 will be swung so as to firmly clamp the line or cable 13 between the slips

10. If for any reason it should be desirable, the screw 26 can be slightly loosened so as to let the clamp slip. This is desirable through certain operations as will be 5 evident to those skilled in this art. To remove the clamp, it is of course, necessary that the screw be rotated so as to allow the slip portions 7 to be swung away from each other.

10 It is thought that the construction, operation, and advantages of this invention will now be clearly understood without a more detailed description thereof. The present embodiment of the invention has been given 15 merely by way of example and attains all the features of advantage enumerated as desirable in the statement of the invention and the above description. It will be apparent that numerous changes in the details 20 of construction, in the sizes, and the materials, in the combination and arrangement of parts as may be resorted to without departing from the spirit or scope of the invention as hereinafter claimed or sacrificing 25 any of its advantages.

Having thus described the invention, what I claim as new and desire to secure by Letters Patent is:—

1. In a clamp of the class described, a 30 rectangularly shaped yoke having its ends provided with inwardly extending fulcrums, a pair of jaws having their outer edges provided with notches for receiving the fulcrums, a pin extending transversely of the yoke and engaging the inner edges of the 35 jaws for holding the notches thereof in engagement with the fulcrums, a screw block pivoted in one end of one jaw, a seat block pivoted in the same end of the other jaw, 40 a screw threaded through the screw block and engageable in the seat block, and slips provided in the other ends of the jaws.

2. In a clamp of the class described, a rectangularly shaped yoke having its ends

provided with inwardly extending fulcrums, a pair of jaws having their outer edges provided with notches for receiving the fulcrums, a pin extending transversely of the yoke and engaging the inner edges of the jaws for holding the notches thereof in engagement with the fulcrums, a screw block pivoted in one end of one jaw, a seat block pivoted in the same end of the other jaw, a screw threaded through the screw block and engageable in the seat block, the other 55 ends of said jaws being provided with transversely extending slip receiving portions having their upper ends provided with outwardly and downwardly curved hooks and their inner edges provided with tapered 60 grooves, tapered slips receivable in said grooves.

3. In a clamp of the class described, a rectangularly shaped yoke having its ends provided with inwardly extending fulcrums, 65 a pair of jaws having their outer edges provided with notches for receiving the fulcrums, a pin extending transversely of the yoke and engaging the inner edges of the jaws for holding the notches thereof in 70 engagement with the fulcrums, a screw block pivoted in one end of one jaw, a seat block pivoted in the same end of the other jaw, a screw threaded through the screw block and engageable in the seat block, the other 75 ends of said jaws being provided with transversely extending slip receiving portions having their upper ends provided with outwardly and downwardly curved hooks and their inner edges provided with tapered 80 grooves, tapered slips receivable in said grooves, said slips provided with lateral extensions at their upper ends provided with openings, and screws extending through said openings into the upper ends of the 85 portions.

In testimony whereof I affix my signature.

BERNARD J. GARNER.
